METHOD AND CIRCUIT FOR COMPENSATING
FOR NON-UNIFORMITIES IN DISPLAY STORAGE
TUBES

Howard M. Scott, Philadelphia, Pa., and Claude E. Reeder, Pennsauken, N.J., assignors to Radio Corporation of America, a corporation of Delaware

Filed Oct. 4, 1960, Ser. No. 60,370
9 Claims. (Cl. 315—12)

This invention relates to signal storage and display and particularly to improved methods and means for utilizing a display type electrical storage tube for displaying signal intelligence.

In display storage tubes of the general type shown in Knoll Patent 2,856,559 and in Hook Patent 2,843,798 a picture is obtained by causing a focused writing beam to produce a charge pattern on a storage screen. The writing beam is intensity modulated as it scans the storage screen, thus laying down the charge pattern.

The storage tube also includes a viewing gun that directs a spray of electrons (a viewing beam) toward the storage screen. Behind the storage screen is a viewing screen such as a phosphor screen. The tube structure also includes a collector screen on the beam side of the storage screen which is spaced close to the storage screen.

Electrons of the viewing beam pass through the interstices of the storage screen as a function of the charge pattern laid down on the storage screen, and strike the phosphor screen to produce a picture thereon that corresponds to the charge pattern.

In manufacturing storage tubes of this type it is difficult to produce tubes that do not have non-uniformities such as slight variations in spacing between the electrodes, especially the collector screen, the storage screen, and the phosphor screen. Still other non-uniformities may result from the collimator electrodes of the tube and the density of the viewing beam. Also, the angle at which the writing beam strikes the storage grid may reduce the amount of the stored charge because at the large angles the collector screen may absorb some of the writing beam energy.

As a result of such variations in uniformity, the picture appearing on the phosphor screen of a display storage tube may have a non-uniform background. For example, the background may contain light and dark areas or spots, or one half of the picture may have a darker background than the other half, or there may be light and dark rings. In addition to the fact that such a picture is not pleasing to the observer, some of the picture information may be lost because of poor halftone display at the very low light levels.

An object of the invention is to provide improved methods of and means for reducing the above-described adverse effects on the picture of a display storage tube.

A further object of the invention is to provide methods of and means for producing an improved picture on a display storage tube.

A further object of the invention is to provide an improved signal display system.

A still further object of the invention is to provide improved methods of operating a display storage tube.

In practicing one embodiment of the invention, a small amplitude sine wave or other repetitive voltage, referred to as a compensating voltage, and having a 400 cycle frequency, for example, is applied between the storage screen and, for example, the cathode of the viewing gun of the tube. As a result, formerly black screen areas are periodically brightened so that a picture of improved background is obtained. Also, as will be explained here-

2

inafter, certain picture information that formerly was obscured is displayed in an improved manner.

The invention will be described in detail with reference to the accompanying drawing in which:

FIG. 1 is a cross-sectional schematic diagram, partially in block form, of a display storage tube system embodying the invention;

FIG. 2 is a schematic diagram, in block form, of a modification of the system shown in FIG. 1;

FIG. 3 is a schematic circuit diagram illustrating a modification of the system shown in FIG. 1;

FIG. 4 is a group of graphs which are referred to in explaining the invention; and

FIG. 5 is a group of graphs corresponding to a portion of FIG. 4 on an enlarged scale.

Similar reference characters are applied to similar elements throughout the drawing.

For an understanding of the invention one should first understand the construction and operation of display storage tubes. The description which immediately follows under the headings "Storage Tube Structure," "Tube Operation" and "Erasing" is for the purpose of providing this preliminary understanding of display storage tubes and their operation.

The later section under the heading "Compensation for Providing Improved Halftone Response and for Providing More Uniform Background" relates specifically to the present invention as applied to display storage tubes.

Storage Tube Structure

FIG. 1 of the drawing shows one example of a display type storage tube consisting of an evacuated envelope 10 having two neck sections 12 and 14, respectively. Within the envelope neck 12 is an electron gun 16, hereinafter referred to as the "viewing gun." Within neck 14 is a second or "writing" electron gun 18 for providing a modulated beam of electrons which is accelerated into the envelope portion 10.

Mounted at the large end of the envelope portion 10 is a phosphor screen assembly 20 including a glass support sheet 22 having a thin conductive film 24 disposed on one surface thereof and facing the electron guns. The film 24 may be formed, for example, of a metal or metallic compound such as tin oxide. On top of the conductive film 24 is a layer 26 formed from a phosphor material which fluoresces under electron bombardment.

In the direction towards the electron guns from the surface of the fluorescent layer 26 is a storage screen 27 which includes a fine mesh metal screen 28 spaced at a distance of two or more millimeters, for example, from the fluorescent layer 26. The storage screen 27 further includes capacitive or storage elements 30 on the metal screen 28.

The capacitive elements 30 may be formed, for example, by evaporating on the surface of the metal screen 28 a dielectric insulating material such as silica or magnesium fluoride to form thereon a film of the order of several microns in thickness. The metal screen 28 is referred to as the backing-electrode of the storage screen 27. A second fine mesh metal screen 32, which is referred to as the collector screen, is located a few millimeters from the storage screen 27 in the direction towards the electron guns. Screen 32 may be a woven stainless steel screen of the order of 230 lines per inch while the conductive screen 28 and the storage screen 27 may have a fineness of the order of 200 lines per inch.

The phosphor screen assembly 20 and the storage screen 27 are mounted on an annular metal support ring 40. The ring 40 supports intermediate its ends the glass support sheet 22 and across its open end the conductive screen 28. The support ring 40 is mounted on a ring 36

of insulating material. The ring 35 is fixed within the envelope by supporting means not shown. Also mounted on the insulating ring 36 is a second annular metal support ring 42 across the end of which is mounted the woven metal mesh screen 32. The conductive tin oxide film 24 is insulated from the support ring 42 by the glass sheet 22 and is connected by a lead 44 to a source of positive potential outside the envelope 10. Mesh screen 32 also is connected to a source of positive potential via lead 46. The conductive screen 28 of the storage screen during the tube operation, is set either at ground potential or a bias potential for writing or at a more positive potential of the order of twenty volts, for example, for erasure, as will be shown hereinafter.

The viewing gun 16 comprises a cathode electrode 48, a control electrode 50, a first accelerating electrode 52, and a second accelerating electrode 54 mounted successively along the axis of the gun 16 toward the face plate 38. During the tube operation these electrodes are maintained at appropriate voltages to form the electron emission from the cathode 48 into a wide beam or spray 56 of electrons which is referred to as the viewing beam. The inner surface of the envelope 10 has applied thereto a conductive coating 58 of colloidal graphite which coating may be maintained at the same positive potential as the second accelerating electrode 54. A second wall coating 60 extends from a point spaced from but adjacent coating 58 over the bulb wall enclosing the assemblies 20 and 27. This coating is at a potential different from that of coating 58 and thus provides a collimating electron lens to align the electrons of the spray beam 56 in a direction axially with respect to the target assemblies.

The writing electron gun 18 comprises a cathode electrode 62, a control electrode 64 and, successively spaced toward the target, a first accelerating electrode 66 and a second accelerating electrode 68. The wall coating 58 extends into the neck 14 of the writing gun and forms a third accelerating electrode for forming the electrons of gun 18 into a sharply defined and focussed beam 70.

The voltages indicated in FIG. 1 as applied to the electrodes of the above tube are illustrative of typical suitable operating voltages but should not be considered as limiting.

Tube Operation

To prepare the storage target for storing a charge pattern on the capacitive elements 30 of the storage screen 27, it is necessary to establish a uniform potential thereover. With the viewing gun turned on, the electrons of the spray beam 56 are accelerated with energies up to 1,000 volts through the metal mesh screen 32. The potential of conductive screen 28 of the storage screen is set to a potential sufficiently positive (of the order of 20 volts positive relative to ground, for example) that the electrons of the viewing beam 56 strike the storage surface 30 of the storage screen at velocities or energies to initiate secondary emission from all portions of the surface. In the present example, the positive potential of 20 volts, which may be an erase pulse, is applied, as described hereinafter, to the conductive screen 28 is below the first cross-over point on the secondary ratio curve of the silica (or magnesium fluoride) film. The first cross-over point for a silica storage film is of the order of 75 to 150 volts while the first cross-over point for a magnesium fluoride film is approximately 30 to 60 volts. Thus secondary emission is initiated having a ratio less than unity and the storage screen surface 30 assumes a uniform potential, in this instance viewing gun cathode potential. The entire surface of the storage screen may be completely erased to a uniform potential, as described above, in a fraction of a second.

The potential applied to the conductive screen 28 of the storage screen is then set to approximately ground potential. In some cases it may be desirable to apply either a small positive bias or a small negative bias to the

screen 28. Because of the thinness of the storage surface 30 of the storage screen, the surface 30 is closely coupled capacitively to the backing screen 28, hence the relative potential difference therebetween is maintained; i.e., as the potential of screen 28 is changed from a 20 volts positive relative to ground (as by erase pulses discussed hereinafter) to ground potential, the potential of screen surface 30 changes by a corresponding amount from viewing gun cathode potential (ground potential) to approximately minus 20 volts relative to ground, i.e., the screen surface 30 assumes a minus 20 volt bias. The electrons of the viewing beam 56 are accelerated through the collector screen 32 and enter a retarding field adjacent the screen surface 30, the retarding field turning the electrons back to the metal screen 32 which serves as a collector therefor. The 8,000 volt potential applied to the tin oxide film 24 of the phosphor screen creates a field which tends to extend through the interstices of the storage screen 27 to draw electrons through the screen to bombard the fluorescent layer 26. The voltage to which the storage screen surface 30 is set (minus 20 volts), however, just prevents any electrons from passing therethrough. This is referred to as the viewing beam cut-off voltage.

The writing gun 18 is then turned on and produces a sharply defined and focused beam 70 which may be deflected to scan over the storage surface 30. The deflection may be accomplished, for example, by supplying vertical and horizontal pairs of deflection plates 72 and 74, respectively, with suitable deflection signals from deflection generators 76 and 78, respectively. While the writing beam 70 is being deflected in the desired pattern, the beam 70 is modulated by video signals applied to the writing gun control grid 64 from an input circuit 80. The writing beam 70 impinges on the storage surface 30 at a voltage of approximately 3,000 volts which is between the first and second cross-over points on the secondary emission ratio curve thereof.

In this manner the writing beam initiates secondary emission from the surface of the storage screen such that more electrons leave the surface than impinge thereon. In those areas where the beam 70 strikes, the storage elements 30 of the storage screen are driven positively from their potential of minus 20 volts toward viewing gun cathode potential or ground. Provided the ratio of the viewing beam average current density to the average current density of the writing beam over a given time is unity or greater, no point on the storage surface 30 will stay positively charged with respect to ground since electrons from the viewing beam 56 land continuously at that point and drive it back to ground potential, or slightly negative with respect to ground. In the areas where the storage surface 30 has been driven positively (from minus 20 volts) the positive field of the phosphor screen 26 now penetrates to draw the low energy electrons of the viewing beam 56 through the interstices of storage screen 27 to strike the phosphor layer 26 and cause luminescence. This luminescence appears only on areas of the phosphor layer 26 corresponding to areas of the storage surface 30 driven positively by secondary emission and hence corresponding to the image pattern of the writing beam.

This type of writing provides a visual display in which stored information appears as "white" on a dark background. Once a signal has been stored and displayed, theoretically it should remain stored and displayed indefinitely since the mode of tube operation described above is such that the low velocity viewing beam 56 normally does not come in contact with the charged areas of the storage surface 30 and therefore does not disturb the established charge pattern.

Erasing

FIG. 1 shows a suitable erasing system for use with the display storage tube. This system is adapted for

through a coupling capacitor and through the diode 104 to the high potential end of the load resistor 92. A positive bias from a battery 103 is applied to the anode side of the diode 104 so that it will pass the full compensating voltage. If the compensating voltage is three volts, for example, the bias voltage may be two volts.

Since the erase pulse has a higher peak voltage than the peak-to-peak voltage of the compensating voltage wave, the diode 104 is made non-conducting upon the occurrence of the positive potential erase pulse. Thus, the compensating voltage is never superimposed on the erase pulse.

The relation of the value of the compensating voltage 102 to the pertinent characteristics of a particular display storage tube may be understood by reference to FIG. 4.

The graphs A—A' and A—A'' are obtained from a particular display storage tube by plotting the brightness or luminosity of the phosphor screen against the voltage of the storage elements 30 of the storage screen 27. This will be understood from the following description of how the graphs are obtained.

The writing beam is turned off and the viewing beam is turned on. Also, the oscillator 101 is turned off or disconnected. The storage screen is soon at an equilibrium condition and the phosphor screen is at a uniform white. The storage elements of the storage screen 27 have now been brought to the potential of the cathode of the viewing gun by the viewing beam electrons.

Next an erase pulse of comparatively small voltage is applied to the storage screen. The peak amplitude of the erase pulse voltage may be such as to reduce the screen brightness down to the point 1 on the graph, for example. The erase pulse amplitude is then increased to reduce the phosphor screen brightness still further to the point 2, for example.

It will be understood that the erase pulses of a selected peak amplitude are applied for a period long enough to effect the maximum erase or brightness reducing effect that will be produced by pulses of the particular amplitude selected. It may be noted that the abscissa voltage representing the voltage of the storage elements 30 of the storage screen is the same as the peak voltage amplitude of the erase pulses. Thus, point 1 may be plotted from the amplitude of the applied erase pulse and from the resulting brightness of the phosphor screen.

As this plotting is continued by successively increasing the voltage of the erase pulse it will be found that some area or areas of the phosphor screen will become darker than other areas. This is the non-uniform background effect due to the tube non-uniformities previously mentioned. For example, the graph A may continue along the graph section A''. The graph A—A'' in the illustration is the graph for the screen area or spot that goes black first as the erase pulse is successively increased in amplitude for the plotting; it is the graph for the minimum viewing beam cut-off. In the example, a spot on the screen has gone black at the point labeled "cut-off point for darkest spot." The graph A—A' may now be plotted for the lightest area or spot on the phosphor screen. This is the graph for the maximum viewing beam cut-off. It will be apparent that the storage screen had to be brought to a more negative voltage to make this "lightest area" go black as indicated by the legend "cut-off point for brightest spot."

The difference between these two cut-off voltages is indicated as ΔV . In the example illustrated in FIG. 4 the compensating voltage 102 applied to the storage screen has a peak-to-peak value of about two times ΔV .

The operation of a display storage tube using the compensating voltage wave 102 will now be described with reference to FIG. 4. In the description it will be assumed that, as described in connection with FIG. 3, the erase pulse and the compensating voltage do not add. The peak amplitude of the erase pulse is set to a value

5

such that it brings the storage elements 30 of the storage screen to an intermediate potential between the cut-off potentials for the darkest spot and the lightest spot. In the example illustrated, this intermediate potential (the bias potential) is midway between the two cut-off potentials. In order to simplify the description, an operation is assumed where complete erasure is effected at the end of a picture frame, i.e., during the frame return time.

At the beginning of the next picture frame, the erase pulse is off and the storage elements 30 of the storage screen have their potential changed with respect to ground in accordance with the applied compensating voltage wave 102. This is because the capacity elements 30 are disconnected or "floating" since the electrons of the viewing beam no longer strike them, the erase pulse being off.

10

It is evident from FIG. 4 that one-half cycle of the voltage wave 102 swings the storage elements 30 of the storage screen less negative so that the darkest spot on the phosphor screen will become light, i.e., no longer black. It follows that the entire surface of the phosphor screen momentarily becomes light. This result is plotted in FIG. 4 which shows that now the darkest spot area of the screen periodically has the brightness indicated by the graphs 109. It is apparent that some picture information that might have been lost without using the compensating voltage now is not lost, and that no spot on the screen will appear black.

20

A similar plotting with respect to the graph A—A' for the lightest spot on the phosphor screen shows that this area of the phosphor screen has the brightness indicated by the graphs 111. As a result of the compensation, this area may be slightly increased in effective brightness, it may be substantially unchanged, or it may be decreased in effective brightness, depending upon tube characteristics and adjustments.

25

It will be noted that the other half cycle of the compensating voltage causes the entire surface of the phosphor screen to become black momentarily. Thus, in the example illustrated the entire phosphor screen surfaces goes alternately light and black.

30

In the foregoing discussion it is assumed that the writing beam is not laying down a charge on the screen areas being considered, that is, certain areas corresponding to the graphs A—A' and A—A''. During operation a writing beam, if modulated, will lay down charges on some or possibly all areas of the storage screen, but the effect of the compensating voltage is best illustrated by assuming that no charges are laid down on at least one area of "darkest spot" and one area of "lightest spot."

35

In addition to providing more picture information, the use of the compensating voltage makes the picture background less spotty, i.e., more uniform and less contrasty. It will be helpful to refer to FIG. 5 in discussing how the picture background is made less contrasty. In FIG. 5 the graphs correspond to those in FIG. 4 with the lower portions of the graphs A—A' and A—A'' enlarged for more accurate plotting.

40

A comparison of the background contrast for two conditions will be made. The first condition is where the erased storage screen has no compensating voltage wave on it and is biased by the amount of the peak amplitude of the erase pulse. For the dark screen area (graph A'') the light level is black. For the brightest screen area (graph A') the light level is represented by line 112. The amount of contrast is indicated by the double arrow 113.

45

The second condition is where the erased storage screen has the compensating voltage 102 applied to it. For the dark screen area (graph A'') the light produced on the phosphor screen is represented by graph 109. The apparent brightness is the average brightness for the time the area is not black (represented by dotted rectangle 114) times the percentage of the complete cycle period that the area is light. This percentage in the illustration is about one-third. Therefore, the light level (apparent

cyclically and incrementally erasing data stored and displayed thereby. A synchronizer 82 repetitively produces pulses at a predetermined pulse repetition rate. These pulses are fed to a horizontal deflection wave generator 78 and to a pulse rate divider circuit 84. The divider circuit produces one output pulse in response to a predetermined number of input pulses. Assuming that the erasing is to be utilized in connection with a typical B-scan radar system, the divider circuit 84 may produce one output pulse in response to each 6,000 pulses input thereto. This assumes a synchronizer pulse repetition rate of 1,000 cycles per second and an azimuth scanning rate of one 360° search every six seconds. Each output pulse derived from the divider 84 is applied to a vertical deflection wave generator 76. The horizontal and vertical deflection generators 78 and 76, respectively, produce saw-tooth deflection signals which are applied to the pairs of deflection plates 72 and 74 of the storage tube to deflect the writing beam 70 to rectilinearly scan the storage surface 30.

During the horizontal deflection intervals, video signals are applied to the writing gun control electrode 64 via input circuit 80. They modulate the intensity of the writing beam 70 to establish a predetermined charge pattern on the storage surface 30 and a corresponding visual display on the phosphor layer 26.

Simultaneous with the application of synchronizer pulses to the divider circuit 84 and to the horizontal deflection generator 78, the synchronizer pulses also are successively applied to a time delay circuit 86 and to a one-shot multivibrator 88. The time delay provided by the circuit 86 is adjusted such that the leading edges of the one-shot multivibrator pulses each occur slightly after the writing of each line of information. The multivibrator pulses thus produced are applied to an amplifier 90, preferably a cathode-follower. The output pulses 89 (the erase pulses) of amplifier 90 are supplied through a coupling capacitor 91 and an isolating resistor 93 to a load impedance 92 connected between the conductive screen 28 and ground so as to periodically and instantaneously drive the conductive screen 28 approximately 20 volts positive with respect to ground potential to effect partial erasure of the stored data. By this means information stored in the display tube incrementally is erased in the "flyback" interval following each writing interval.

The erase interval may be controlled by controlling the multivibrator pulse duration and the extent or "depth" of erasure may be controlled by suitable adjustment of the amplitude of the erasing pulse. The erasing pulse duration may be controlled, for example, by varying circuit constants in the charging circuit of the one-shot multivibrator 88 while the erasing pulse amplitude may be controlled by means of a gain control circuit 94 associated with the amplifier 90. By properly adjusting the amplitude and duration of the erasing pulse, it will be seen that a given line of data is partially erased during each flyback interval and is completely erased in one frame time and just prior to being replaced with a line of new data. Thus an up-to-date display of information is provided wherein old data cyclically may be erased and replaced with new information.

Signal integration and noise discrimination may be afforded by employing the system shown in FIG. 2 of the drawing. Signals applied to the input of the time delay circuit 86 are derived from the output circuit, rather than the input circuit, of the pulse rate divider circuit 84. Thus erasing pulses are produced only in the time intervals between the writing of successive frames of information.

In the mode of operation for obtaining signal integration, both desired signals and noise signals are written during a given frame time and are partially erased just prior to the writing of the next frame of data. In the next frame time the desired (and partially erased) sig-

nals are rewritten to enhance the charge pattern established during the writing of the preceding frame. The noise signals, however, because of their random occurrence are not rewritten in the same areas on the tube storage screen 30 in successive frames. Thus the desired signals are integrated and noise signals are erased.

Another mode of operation for the system of FIG. 2 may be employed. In this mode of operation complete erasure at the end of each picture frame is effected, there being no signal integration in this case.

In the foregoing description, the erase pulse is described as synchronized with the deflection waves. It should be understood that such synchronization is not necessary, and that the present invention applies equally well to a storage tube system in which the erase pulses are not synchronized with the deflection.

Also, it may be noted that the peak amplitude of the erase pulse depends upon the particular storage tube construction. Thus, instead of an erase pulse of 20 volts as assumed in the example, one storage tube may be operated with a 5 volt erase pulse, and another tube with a 12 volt erase pulse.

Compensation for Providing Improved Halftone Response and for Providing More Uniform Background

In accordance with the present invention the potential of the storage screen is varied repetitively with respect to the cathode of the viewing gun. This may be done, as shown in FIG. 1, by means of an oscillator 101 which has one terminal connected to ground (the cathode of the viewing gun is also connected to ground), and which has the other terminal connected to the backing-electrode 28 of the storage screen 27 through a coupling capacitor 95 and an isolating resistor 97. The oscillator 101 may be a sine wave oscillator or it may be one that supplies a non-sinusoidal wave. For example, it may be a multivibrator that supplies a square wave, or an oscillator that supplies a sawtooth or triangular wave.

The frequency of the compensating voltage 102 supplied by oscillator 101 preferably is at least equal to that corresponding to the period for persistence of vision. The frequency otherwise is largely a matter of convenience. Examples of satisfactory frequencies are 60 cycles per second, 400 cycles per second, and 10,000 cycles per second.

The proper peak-to-peak value of the compensating voltage supplied by oscillator 101 depends upon the particular storage tube. For some tubes one volt peak-to-peak is satisfactory. For other storage tubes six volts peak-to-peak may be desirable. In general, the peak-to-peak value of the compensating voltage less than the peak value of the erase pulse 89, whether a bias is used on the storage screen or not. For example, the peak value of the erase pulse may be from 1½ to 5 times the peak-to-peak value of the compensating voltage, depending upon the particular storage tube and the conditions of operation. These relative values are merely by way of example, and are not to be taken as limiting.

In the circuit shown in FIG. 1 the compensating voltage 102 and the erase pulse 89 will add in load resistor 92. As a result, the compensating voltage 102 will be superimposed on the erase pulse when it occurs. When the two voltages do superimpose, it may be desirable to synchronize them, but usually it is immaterial whether they are synchronized or not. It may be preferred that the peak amplitude of the erase pulse be independent of the compensating voltage. This result may be obtained by employing a non-additive combining circuit such as shown in FIG. 3. This circuit includes diodes 103 and 104. The erase pulse is applied through a coupling capacitor and the diode 103 to the high potential end of load resistor 92. A high impedance resistor 105 prevents the coupling capacitor from acquiring a direct-current charge.

The compensating voltage is applied from source 101

brightness) as the dark screen area is at the level shown in line 116.

For the light screen area (graph A') the light produced is represented by graph 111. The apparent brightness or light level for this area is shown by the line 117. The amount of contrast between the two light levels is indicated by the double arrow 118. A comparison of the two double arrows shows that the contrast is less than it was before the compensating voltage was used.

Of more importance than this comparison, however, is the fact that there are now no black areas in the picture background. The formerly black areas are at least a dark gray. This fact tends to reduce greatly the contrast because the eye is much more responsive to low level light than to higher level light. For this reason, the light level represented by line 116 appears to the eye to be closer to the level 117 than it actually is. As a result, in the example illustrated, the compensating voltage causes a reduction in background contrast that is very substantial.

The measure of contrast may also be expressed as the ratio of the difference in brightness of two regions divided by the brightness of the region considered to be the background. Expressed in this way, the contrast when using the compensating voltage is the value represented by double arrow line 118 divided by the value x . Without the compensating voltage, the contrast would have a larger value equal to the value represented by double arrow line 113 divided by some value much smaller than the value x .

While, for purpose of explanation, complete erasure at the end of a picture frame was assumed, it should be understood the invention applies equally well to systems employing partial erasure such as described in connection with the circuits of FIGS. 1 and 2. This is true whether the erasure is line by line or frame by frame.

It should be noted that the desired reduction in background contrast cannot be obtained merely by reducing the amplitude of the erasure pulse so that no area of the screen goes black. For example, referring to FIG. 5, assume that the erase pulse is reduced in amplitude so that the storage screen is biased back by the voltage z , there being no compensating voltage. While the light level for the dark areas is now the same as in the example using a compensating voltage, the contrast is y/x which is a much higher value than the contrast value obtained by using the compensating voltage.

The invention is applicable regardless of the scanning rates employed in the storage tube system. For example, the scanning rates may be those commonly employed in television. On the other hand, it may be desirable to use the storage tube for storing a picture for a long time, such as several minutes; in which case the erasure may be done under manual control. Here the invention also applies.

What is claimed is:

1. In combination, a display storage tube of the type having an electron permeable storage screen comprising storage elements on which a charge pattern is to be written, means for producing a writing beam for laying down said charge pattern, means including an electron source for producing a spray of electrons and directing them as a viewing beam toward said storage screen, a viewing screen positioned to receive any electrons of said viewing beam that pass through said storage screen, means for erasing a charge pattern from said storage element and thereby negatively biasing said storage elements with respect to said electron source, and means for repetitively varying the potential of said storage elements with respect to said electron source, said repetitive potential variation having a peak to peak amplitude that is substantially less than the potential to which said storage elements are biased.

2. In combination, a display storage tube of the type having an electron permeable storage screen comprising storage elements on which a charge pattern is to be written, means for producing a writing beam for laying down said charge pattern, means including an electron source

for producing a spray of electrons and directing them as a viewing beam toward said storage screen, a viewing screen positioned to receive any electrons of said viewing beam that pass through said storage screen, means for erasing a charge pattern from said storage elements and thereby negatively biasing said storage elements with respect to said electron source, and means for repetitively varying the potential of said storage elements with respect to said electron source, said repetitive potential variation having a peak to peak amplitude that is substantially less than the potential to which said storage elements are biased and having a rate that is at least equal to that of persistence of vision.

3. In combination, a display storage tube of the type having an electron permeable storage screen comprising storage elements on which a charge pattern is to be written, means for producing a writing beam for laying down said charge pattern, means including an electron source for producing a spray of electrons and directing them as a viewing beam toward said storage screen, a viewing screen positioned to receive any electrons of said viewing beam that pass through said storage screen, means including an erase voltage pulse source for negatively biasing said storage elements with respect to said electron source, and means for repetitively varying the potential of said storage elements with respect to said electron source, said repetitive potential variation having a peak to peak amplitude that is substantially less than the potential to which said storage elements are biased.

4. In combination, a display storage tube of the type having an electron permeable storage screen comprising storage elements on which a charge pattern is to be written, means for producing a writing beam for laying down said charge pattern, means including an electron source for producing a spray of electrons and directing them as a viewing beam toward said storage screen, a viewing screen positioned to receive any electrons of said viewing beam that pass through said storage screen, said tube having the undesired characteristic that the viewing beam cut-off potential is different for some areas of the viewing screen than for other areas, means for erasing a charge pattern from said storage elements and thereby negatively biasing said storage elements with respect to said electron source, and means for repetitively varying the potential of said storage elements with respect to said electron source, said repetitive potential variation having a peak to peak amplitude that is substantially less than the potential to which said storage elements are biased but which is large enough to make the potential of said storage elements alternately more negative than the maximum viewing beam cut-off potential for the tube and less negative than the minimum viewing beam cut-off potential for the tube.

5. In combination, a display storage tube of the type having an electron permeable storage screen comprising storage elements on which a charge pattern is to be written, means for producing a writing beam for laying down said charge pattern, means including an electron source for producing a spray of electrons and directing them as a viewing beam toward said storage screen, a viewing screen positioned to receive any electrons of said viewing beam that pass through said storage screen, said tube having the undesired characteristic that the viewing beam cut-off potential is different for some areas of the viewing screen than for other areas, means for erasing a charge pattern from said storage elements and thereby negatively biasing said storage elements with respect to said electron source, and means for repetitively varying the potential of said storage elements with respect to said electron source at a rate that is at least equal to that of persistence of vision, said repetitive potential variation having a peak to peak amplitude that is substantially less than the potential to which said storage elements are biased but which is large enough to make the viewing screen go alter-

nately entirely light and entirely dark with the storage screen in the erased condition.

6. In combination, a display storage tube of the type having an electron permeable storage screen on which a charge pattern is to be written, means for producing a writing beam for laying down said charge pattern, means including an electron source for producing a spray of electrons and directing them as a viewing beam toward said storage screen, a phosphor screen positioned to receive any electrons of said spray of electrons that pass through said storage screen, said tube having the undesired characteristic that the viewing beam cut-off potential is different for some areas of the phosphor screen than for other areas, means for producing an erase voltage pulse having a certain peak amplitude, means for applying said erase voltage pulse to said storage tube for pulsing said storage screen with respect to said electron source, and means for applying to said storage tube a repetitive voltage for varying the potential of said storage screen with respect to said electron source, said repetitive voltage having a peak to peak amplitude that is less than the peak amplitude of said erase voltage pulse but which is large enough to make the phosphor screen go alternately entirely light and entirely dark with the storage screen in the erased condition.

7. In combination, a display storage tube of the type having an electron permeable storage screen on which a charge pattern is to be written, means for producing a writing beam for laying down said charge pattern, means including an electron source for producing a spray of electrons and directing them as a viewing beam toward said storage screen, a phosphor screen positioned to receive viewing beam electrons that pass through said storage screen, said storage tube having the characteristic that the viewing beam cut-off potential is a certain value for one area of the phosphor screen and is a different value for a different area of the phosphor screen, said cut-off potential being a maximum for one of said areas and a minimum for another one of said areas, the voltage difference between said maximum and minimum cut-off potentials being ΔV , means for producing an erase voltage having a certain peak amplitude, means for applying said erase voltage to said storage tube for changing the potential of said storage screen with respect to said electron source, and means for applying to said storage tube a repetitive voltage for varying the potential of the storage elements of said storage screen with respect to said electron source, said repetitive voltage having a peak to peak amplitude that is larger than ΔV but substantially less than the peak amplitude of said erase voltage.

8. In combination, a display storage tube of the type having an electron permeable storage screen on which a charge pattern is to be written, means for producing a writing beam for laying down said charge pattern, means including an electron source for producing a spray of elec-

trons and directing them as a viewing beam toward said storage screen, a phosphor screen positioned to receive viewing beam electrons that pass through said storage screen, said storage tube having the characteristic that the viewing beam cut-off potential is a certain value for one area of the phosphor screen and is a different value for a different area of the phosphor screen, said cut-off potential being a maximum for one of said areas and a minimum for another one of said areas, means for producing an erase voltage pulse having a peak amplitude that is intermediate said maximum and minimum cut-off potentials, means for applying said erase voltage pulse to said storage tube for pulsing said storage screen with respect to said electron source, and means for applying to said storage tube a repetitive voltage for varying the potential of the storage elements of said storage screen with respect to said electron source, said repetitive voltage having a peak to peak amplitude that is smaller than the peak amplitude of said erase voltage pulse but which is large enough to make the potential of said storage elements alternately more negative than the maximum viewing beam cut-off potential for the tube and less negative than the minimum viewing beam cut-off potential for the tube.

9. A signal storage system including, an electrical storage tube having an electron permeable charge storage member, means spaced from one side of said charge storage member for providing a stream of electrons for flooding a major portion of the surface of said member, a viewing screen spaced from the opposite side of said charge storage member, means for providing a sharply defined and focused beam of electrons, means for deflecting said sharply defined and focused electron beam across said storage member, connection means for a source of signals for modulating said beam during said deflection to write an electrical charge pattern on said member, the charge pattern written on said member modulating the flow of said stream of electrons so that electrons passing through said electron permeable member impinge on said viewing screen and produce a visual display corresponding to said charge pattern, means coupled to said storage tube for repetitively generating pulses at a predetermined pulse repetition rate for periodically pulsing said charge storage member with respect to said flood beam generating means, and means for applying to said storage tube a periodic voltage of small peak amplitude as compared with the peak amplitude of said pulses for varying the potential of said charge storage member with respect to said flood beam generating means.
